COMBINED BAR AND STEREO CABINET UNIT

William H. Woods, 97 W. Norwood,
Memphis, Tenn. 35109

Filed Mar. 4, 1969, Ser. No. 16,021

Term of patent 14 years

Int. Cl. D6—01

U.S. Cl. D33—19

FIG. 1

FIG. 2

FIG. 3

FIG. 4

FIG. 1 is an end elevational view of a combined bar and stereo cabinet unit showing my new design.

FIG. 2 is a front elevational view.

FIG. 3 is a rear elevational view.

FIG. 4 is a perspective view.
The end not shown has substantially the same appearance as the end shown in FIG. 1.

I claim:

The ornamental design for a combined bar and stereo cabinet unit, as shown and described.
